UNITED STATES PATENT OFFICE.

HENRY PHILIP ALLIN, OF CAMBRIDGE, ENGLAND.

INDICATOR FOR TAXICABS.

1,142,390.

Specification of Letters Patent.

Patented June 8, 1915.

Application filed June 15, 1912, Serial No. 703,864. Renewed April 14, 1915. Serial No. 21,460.

To all whom it may concern:

Be it known that I, HENRY PHILIP ALLIN, a subject of the King of Great Britain, residing at Cambridge, England, have invented a certain new and useful Indicator for Taxicabs, of which the following is a specification.

10 The primary object of the invention is to provide a conspicuous signal to indicate when public vehicles, such as taxicabs, are for hire.

15 Another object is to make the evidence of vacancy of the vehicle readily distinguishable at night by means of a suitable illuminated signal.

20 Another object is to control the illumination of the signal so that it need be illuminated only when the signal is in the active or "for hire" position.

25 The accompanying drawing shows representative constructions in which my invention is embodied, but it is to be understood that the invention is capable of embodiment in different forms.

30 Figure 1 shows my signaling device in this instance arranged upon the roof of a taxicab, a portion of which is shown in a representative way, also a representative form of taximeter and connections and an electric switch. Fig. 2 is a front view of the signal. Fig. 3 is a part sectional side elevation of a modified form of the signal or indicator. Fig. 4 is an enlarged view of a modified form in which two shutters may be 35 employed.

40 Reference character 1 designates the body of the signal which may be, when it is desired to provide illumination, any suitable form of light inclosure, as shown. In the front of the body is an aperture closed by a glass slide 2 bearing the legend "For hire," or other suitable words for the purpose intended. Across the front of the body is journaled a shaft 3 carrying shutter 4 and 45 the shaft is also provided with an arm 5 for the operation of the shutter. A spring 6 which may be coiled about the shaft may be employed to urge the shutter to one of its positions, conveniently toward the dropped or closed position.

50 Any suitable form of taximeter 10 is located usually near the driver, and this is provided with the usual indicator or flag

11. The flag or its shaft is provided in my invention with an arm 12 for the operation 55 of the signal. This arm is connected with the shutter arm 5 by any suitable mechanism, conveniently a flexible cord 13 running over suitably placed pulleys 14, and in some cases if desired a rigid link or rod 15 60 may be employed in the connecting line, as shown.

Within the body 1 is usually provided an electric bulb 20 and the circuit of this element is controlled by a suitable switch 21 65 having an arm 22 connected with link 15.

When the vehicle is for hire, the flag 11 stands in the position shown in full lines in Fig. 1. Arm 12 of the flag-shaft holds down link 15, keeping the switch-arm 22 in 70 contact position, so that lamp 20 is lighted. The arm 12 also holds cord 13 so that shutter 4 is maintained in its raised or opened position, as shown in full lines, and the for hire signal illuminated by the lamp is 75 plainly visible to all passers. When the vehicle is engaged, the operator throws down the flag. By arm 12 the link 15 is pushed up, throwing the switch-arm 22 to off position and extinguishing the lamp, and 80 at the same time the pulley or cord 13 is relaxed and spring 6 closes shutter 4 obscuring completely the for hire sign.

In Fig. 3 is shown an arrangement in which the shutter is carried within the body 85 of the signal. In this form of the invention, the shutter may consist of a glass slide 30 operated by the arm 30^a and the for hire motto in this case is carried by the slide 30. The front aperture of the signal body is 90 closed by a plain glass window 32. In this case the parts are arranged so that when the taximeter flag is put down, showing that the vehicle is for hire, the slide 30 is allowed to drop by the relaxing of cord 13 and the 95 legend is thus brought in front of the lamp behind the window 32. When the vehicle is engaged and the flag is thrown up, the slide is raised as shown in Fig. 3 and the lamp is extinguished.

100 Fig. 4 shows a modification in which both sides of the body 1, looking both toward the front and rear may be provided with suitably marked slides or panels 2^a, and in this case a shutter 50 having a suitable arm 51 is 105 provided for each of the openings. The

shutters are operated from the single cord by means of an elbow link 52 connected to the cord at 53 and at its free ends connected to each of the arms 51 by a pin and slot connection 54.

5 I claim:—

1. A signal for cabs and the like, comprising in combination a taximeter including a lever for rendering the meter operative and inoperative, a lamp body placed on an exposed part of a vehicle, a lamp therein, a transparent slide bearing a legend and located at one side of the lamp body for illumination by the lamp, a shutter movably carried by the lamp body for obscuring and disclosing the slide, and a connection between the shutter and the taximeter.
- 10 2. A signal for cabs and the like, comprising in combination a taximeter including a lever for rendering the meter operative and inoperative, a lamp body placed on an exposed part of a vehicle, a lamp therein, a transparent slide bearing a legend and located at one side of the lamp body for illumination by the lamp, a shutter movably carried by the lamp body for obscuring and disclosing the slide, a connection between the shutter and the taximeter, and means by which movement of the taximeter lever causes said lamp to be lighted when the shutter is raised to disclose the slide and ex-
- 15 20 25

tinguished when the shutter is lowered to conceal the slide.

3. A signal for cabs and the like comprising in combination a taximeter having an operating lever, a lamp body, a transparent slide therein bearing a legend, a pivoted shutter adapted to disclose or conceal the slide, an arm carried by the shutter, a cord or the like connecting said arm with said taximeter lever, and an incandescent lamp within the lamp body for illuminating the slide.

4. A signal for cabs and the like comprising in combination a taximeter having an operating lever, a lamp body, a transparent slide therein bearing a legend, a pivoted shutter adapted to disclose or conceal the slide, an arm carried by the shutter, a cord or the like connecting said arm with said taximeter lever, an incandescent lamp within the lamp body for illuminating the slide, an electric switch in circuit with the lamp and a connection between said switch and said cord whereby the lamp is lighted when the shutter is raised and extinguished when the shutter is lowered.

HENRY PHILIP ALLIN.
